(57) **CLAIM**

The ornamental design for a tray for a liquid dispenser, as shown and described.

DESCRIPTION

FIG. 1 is a perspective view of a tray for a liquid dispenser showing our new design in extended position;

FIG. 2 is a front elevational view thereof;

FIG. 3 is a left side elevational view thereof, the right side being a mirror image;

FIG. 4 is a top plan view thereof;

FIG. 5 is a bottom perspective view thereof;

FIG. 6 is a perspective view of a tray for a liquid dispenser showing our new design in closed position; and,

FIG. 7 is a front elevational view thereof.

The broken lines are included for the purpose of illustrating environment and form no part of the claimed design.
